H. VOLIS

INSIDE MICROMETER GAUGE

Filed Aug. 21, 1924

UNITED STATES PATENT OFFICE.

HARRY VOLIS, OF DETROIT, MICHIGAN, ASSIGNOR TO VOLIS PRECISION TOOL COMPANY, OF DETROIT, MICHIGAN, A CORPORATION OF MICHIGAN.

INSIDE MICROMETER GAUGE.

Application filed August 21, 1924. Serial No. 733,314.

To all whom it may concern:

Be it known that I, HARRY VOLIS, a citizen of the United States, and residing at Detroit, in the county of Wayne and State of Michigan, have invented a new and Improved Inside Micrometer Gauge, of which the following is a specification.

This invention relates to means for accurately determining the diameters of holes in and bores of metal bodies and the object of this invention is to produce an instrument of this character which can be correctly adjusted and which, after it becomes worn, can be readily and correctly readjusted.

A further object of this invention is to produce an instrument of this character which can be readily corrected should its operative surfaces get out of alinement.

This invention consists in a body having longitudinal slots and blades slidably mounted therein and provided with inner edges which are inclined in the same direction, a pair of expanders engaging said inclined edges, means to move said expanders to cause the blades to slide out radially, and means to move one of said expanders relative to the other so as to cause the adjacent ends of the blades to move outwardly or inwardly while their opposite ends are substantially at rest so as to eliminate any taper there may be in the operative portion of the instrument and to bring the operating surfaces of the blades into parallelism.

It further consists in an instrument of this character embodying an indicator and an operating member to move the expanders relative to the blades and provided with a threaded portion engaging a threaded member on the body, the indicator and body being graduated to indicate the exact diameter of the outer surface of the testing blades, the indicator and operating member being relatively movable to permit accurate adjustment of the instrument for diameter.

It further consists of the details of construction illustrated in the accompanying drawing and particularly pointed out in the claims.

In the drawing, Fig. 1 is a plan of this improved inside micrometer gauge. Fig. 2 is a longitudinal section thereof. Figs. 3 and 4 are sections on the lines 3-3 and 4-4 of Fig. 2.

Similar reference characters refer to like parts throughout the several views.

The body of this instrument, that is, that portion which is rigid when assembled, comprises a head 1, a cap 2 secured to the head by means of screws 3, a handle 4 screwed onto the neck 5 of the head and a tubular member 6 screwed into this neck. Except for difficulties in manufacture, the head and tubular member might be integral.

The head 1 is radially and longitudinally slotted to receive the radially sliable blades 8 which are internally grooved to receive the springs 9 whose ends extend into the circular groove 10 in the cap and beneath the circular shoulder 11 of the head. Pins 12 position these springs. The blades have inclined inner edges 14 and 15 which are at the same angle to the axis of the instrument.

A shaft 16 is secured in the cap by means of a screw 17 and a small ball 18 which rides in the groove 19 in the shaft. The shaft may be turned in the head when released by screw driver inserted in the transverse groove 20. On this shaft are slidable the sleeve 22, the bushing 23 in the expander 24 and the bushing 25 in the expander 26. I prefer to form the expanders of hard steel and the bushings of bronze to avoid wear and friction respectively. The expanders have flat inclined surfaces at the same angle as the edges 14 and 15 of the blades. Outward movements of the expanders are resisted by the springs 9 but are effected through the ball bearing 27 and devices to be explained later on. These expanders do not rotate in the head, being prevented by the engagement of their flat surfaces 13 with the ends of the blades.

The pressure of the bearing 27 on the inner end of the bushing 25 is transmitted in part to the sleeve 22 and by that to the bushing 23. The sleeve 22 is slidable on the shaft 16 but cannot rotate thereon because of the screw 28 in this shaft extending into the slot 29 in the sleeve. The angles of the expanders being the same, both ends of the blades 8 will move outwardly the same distance for equal longitudinal movements of the expanders. But should the outer ends of the blades extend outward a greater or less distance than the inner ends, which is the case when the blades become worn, then the screw 17 is released and the

shaft 16 and the sleeve 22 turned relative to the bushing 23 to move the expander 24 inward or outward until the operating surfaces of the blades are in exact parallelism.

5 The end 31 of the tubular member 6 is formed with very uniformly pitched and quite fine threads, preferably forty per inch, and an operating sleeve 32 is externally threaded to fit therein. The inner end of 10 the sleeve 32 engages the bearing 27 so that the expanders are moved outwardly when this sleeve is turned in one direction and are moved inwardly through the pressure of the springs 9 when the sleeve 32 is 15 turned in the opposite direction. If the angle of the operating surfaces of the expanders to the axis of the shaft 16 is thirty degrees and the threads on the sleeve 32 are forty per inch, one rotation of the sleeve 20 will cause the blades to move outwardly .0125 inch and measurements of .0001 of an inch are easily determined.

I prefer to secure an indicating shell or indicator 34 to the operating sleeve 32 and 25 to graduate its tapering outer end 35, and to graduate the middle portion of the tubular member 6 to co-operate with the graduations on the indicator 34. Openings 36 may be formed in the handle 4 through 30 which these graduations may be seen, and when vernier graduations are employed, variations of .0001 inch in the working diameter of this instrument are provided for.

35 The blades are first positioned for a predetermined measurement. The indicator 34 is then accurately positioned on the tubular member 6 so that their graduations indicate the desired diameter. The screw 38 is then 40 forced in to press the ball 39 against the interior surface of the shell which locks the indicator to the operating sleeve. This operating sleeve is mounted on the tubular member 6 and is bored to fit the shaft 16 45 which is therefore supported thereby.

A collar 41 is firmly held in the handle 4 by being a press-fit. An operating connector 42 is rotatably mounted in this collar and its inner end comprises a pair of fingers 50 43 which extend into notches in the adjacent end of the operating sleeve 32. A locking button 44 screws onto the outer end 46 of this connector and an operating collar 45 is slidably but non-rotatably attached to 55 the connector by the pin 47. A spring washer 48 is placed between the button 44 and the shoulder 49 of the collar 45. The inner end of the operating collar 45 and the shoulder 50 of the connector 42 engage the 60 stationary collar 41. A screw 52 carried by the operating collar 45 enters the groove 53 in the locking button and prevents it from getting lost but permits sufficient longitudinal movement of the button.

65 When the locking button is screwed down

onto the threaded end 46 of the connector 42, the spring washer 48 causes the operating collar 45 and the shoulder 50 on the connector to engage the stationary collar 41 of the handle with such force as to prevent 70 movement between them. This also locks the operating sleeve 32 and therefore substantially locks the blades.

When the button 44 is turned back to release the operating collar this may be 75 freely turned to turn the connector 42 and the sleeve 32 and thus cause the expanders to move longitudinally of the blades.

The threads between the portion 31 of the sleeve 6 and the sleeve 32 must be accurately uniform in pitch and the angle of the inclines of both of the expanders must be the same and must be laid out to co-operate with the graduations of the indicator and the tubular member 6. These are 80 matters well within the domain of skilled engineers. The details of construction and proportions and sizes of the parts may also be varied by those skilled in the art without departing from the spirit of my invention 85 as set forth in the following claims.

I claim:—

1. In a gauge, the combination of a hollow cylindrical body having a radial slot, a central shaft in the body, expanders slidably mounted on the shaft and having surfaces inclined to the axis of said shaft, a blade mounted in the slot in engagement with said inclined surfaces on the expanders, means to slide the expanders along the shaft 160 in one direction as a unit to force the blade outwardly, and means to vary the distance between said expanders.

2. In a gauge, the combination of a hollow cylindrical body having a radial slot, a central shaft in the body, expanders slidably mounted on the shaft and having surfaces inclined to the axis of said shaft, a blade mounted in the slot in engagement with said inclined surfaces on the expanders, means to slide the expanders along the shaft 105 in one direction as a unit to force the blade outwardly, resilient means to draw the blade into the slot and to slide the expanders in the opposite direction, and means to vary 110 the distance between said expanders.

3. In a gauge, the combination of a hollow cylindrical body having radial slots, expanders movable longitudinally of the body and having operating surfaces inclined 120 to the axis of said shaft, blades mounted in the slots contacting with the inclined surfaces on the expanders, a tubular extension on the body having a threaded end, an operating member operatively engaging said threaded end and the expanders to force the expanders along the shaft in one direction as a unit to cause the blades to move outwardly, and means to vary the distance 125 between said expanders.

4. In a gauge, the combination of a hollow cylindrical body having radial slots, a central shaft mounted in the body, expanders slidably mounted on the shaft and having surfaces inclined to the axis of said shaft, blades mounted in the slots and provided with inclined surfaces in engagement with the inclined surfaces on the expanders, a tubular extension on the body having an internally threaded end, an operating sleeve engaging said threaded end and the expanders to force the expanders along the shaft in one direction as a unit to cause the blades to move outwardly, and means to vary the distance between said expanders. 65
5. In a gauge, the combination of a hollow cylindrical body having radial slots, a central shaft mounted in the body, expanders slidably mounted on the shaft and having operating surfaces inclined to the axis of said shaft, blades mounted in the slots in engagement with the inclined surfaces on the expanders, a tubular extension on the body having an internally threaded end, and an operating sleeve engaging said threaded end and the expanders to force the expanders along the shaft in one direction as a unit to cause the blades to move outwardly. 70
6. In a gauge, the combination of a hollow cylindrical body having radial slots, a central shaft mounted in the body, expanders slidably mounted on the shaft and having surfaces inclined to the axis of said shaft, blades mounted in the slots in engagement with the inclined surfaces on the expanders, a tubular extension on the body having an internally threaded end, an operating sleeve engaging said threaded end and the expanders to force the expanders along the shaft in one direction as a unit to cause the blades to move outwardly, means to vary the distance between said expanders, a graduated indicator adjustably secured to the operating sleeve, a cylindrical handle attached to the body and provided with openings through which the graduations on the indicator may be observed, an operating collar at the end of the handle connected to the operating sleeve, said collar being rotatable relative to the handle and slidably connected to said operating sleeve. 75
7. In a gauge, the combination of a hollow cylindrical body having radial slots, a central shaft mounted in the body, expanders slidably mounted on the shaft and having surfaces inclined to the axis of said shaft, blades mounted in the slots in engagement with the inclined surfaces on the expanders, a tubular extension on the body having an internally threaded end, an operating sleeve engaging said threaded end and the expanders to force the expanders along the shaft in one direction as a unit to cause the blades to move outwardly, means to vary the distance between said expanders, a graduated indicator adjustably secured to the operating sleeve, a cylindrical handle attached to the body and provided with openings through which the graduations on the indicator may be observed, an operating collar at the end of the handle connected to the operating sleeve, said collar being rotatable relative to the handle and slidably connected to said operating sleeve, and means to lock the collar. 80
8. In a gauge, the combination of a hollow body having an even number of radial slots, blades mounted in said body and having their inner edges formed with surfaces inclined to the axis of said shaft, expanders movable in said body and having surfaces inclined in the same direction in engagement with the inclined surfaces on the blades, a screw to force the expanders to move in one direction, and springs in engagement with the blades to move the expanders in the opposite direction. 85
9. In a gauge, the combination of a hollow body having an even number of radial slots, blades mounted in said body and having their inner edges formed with surfaces inclined to the axis of said shaft, expanders movable in said body and having surfaces inclined in the same direction in engagement with the inclined surfaces on the blades, a screw to force the expanders to move in one direction, and springs to move the expanders in the opposite direction, said blades being longitudinally grooved in their inner edges and said springs being seated in the grooves 90
10. In a gauge, the combination of a hollow body having an even number of radial slots, blades mounted in said body and having their inner edges formed with surfaces inclined to the axis of said shaft, expanders movable in said body and having surfaces inclined in the same direction in engagement with the inclined surfaces on the blades, a screw to force the expanders to move in one direction, and springs to move the expanders in the opposite direction, said blades being longitudinally grooved in their inner edges and said springs being seated in the grooves 95
